R. A. ENDEBROCK

TRUCK CASTER

Filed July 5, 1923

FIG. 3.

FIG. 4.

Robert A. Endebrock, INVENTOR
BY John Elias Jones, ATTORNEY.

Patented Mar. 18, 1924.

1,487,450

UNITED STATES PATENT OFFICE.

ROBERT A. ENDEBROCK, OF CINCINNATI, OHIO.

TRUCK CASTER.

Application filed July 5, 1923. Serial No. 649,698.

To all whom it may concern:

Be it known that I, ROBERT A. ENDEBROCK, a citizen of the United States of America, and a resident of Cincinnati, in the county 5 of Hamilton and State of Ohio, have invented a certain new and useful Improvement in Truck Casters, of which the following is a specification.

This invention relates to ball-bearing 10 swivel-casters that are adapted for use in supporting store or warehouse trucks and the like so that they can be readily moved or shifted from place to place in the transfer of goods and various commodities or articles 15 of manufacture.

The main object of the invention is to not only simplify and regulate the cost of structure of the device but to materially increase or enhance its lasting and wearing qualities 20 and to otherwise impart to it better facilities for repairs and the replacing of parts as well as to afford ready access to all the parts for any desired purpose.

The details of such improved structure 25 are hereinafter clearly and fully described in connection with the accompanying sheet of drawings, in which—

Figure 1 is an axial section, showing the wheel-member dotted; Fig. 2, a plan of the 30 underside of the upper bearing-member or attaching-plate; Fig. 3, a fragmentary vertical section of the lower ends of the spaced pair of pendent hangers or bracket-bearings and the transverse pivot pin or shaft for the 35 caster-wheel, showing my improved simplified means for securing the said pivot pin or shaft in said hangers; Fig 4, a fragmentary vertical section of a modified form of ball-bearing nut-element or lock-ring that 40 is mounted on the lower end of a threaded shank projecting centrally from the bottom-side of said upper attaching-plate; and Fig. 5, a bottom plan view of the lock-ring of Fig. 4.

6 indicates the upper attaching-plate or bearing-member having the radial arms or wings 7 through whose holes 8 the usual fastening-bolts (not shown) are passed for attaching the said bearing-member in using 50 position.

9 is a vertical shank or stud projecting downwardly from the center of the upper load-bearing member 6 and having its lower portion screw-threaded. Its bottom face 55 is plane and parallel to that of its plane up-

per face and it has a downwardly-projecting circular peripheral flange 10.

11 indicates the circular lower turn-table or carrier-member of the caster having projecting from its bottom a pair of separated 60 or spaced vertical hangers or bracket-bearings 12, 13, the hanger 12 having at its lower end a vertical screw-threaded opening or hole 14, as shown in Fig. 1 (dotted) and in Fig. 3.

15 indicates a transverse pin or shaft secured or resting at its opposite ends in alined holes 16, 16, made in the lower ends of the said hangers 12 and 13, the opposite ends of such pin or shaft being made flush with 70 the outer faces of the said hangers so that they do not come into contact with any objects in the path of the caster. A vertical screw-threaded pin or set-screw 17 is inserted in the threaded hole 14 in the lower 75 end of the hanger 12 and it has a pointed inner end that engages a shallow notch or socket made in the face of the transverse pin or shaft 15 to prevent the latter escaping or shifting lengthwise, or its release 80 from place in the said hangers 12 and 13 accidentally.

The hub of the wheel (rim thereof dotted at 18) is loosely mounted on the said shaft 15 so that it may rotate thereon in the use 85 of the caster. It is obvious that another set-screw, similar to the one 17, can be used in the lower end of the companion hanger 13 in order to derive greater securing effect to the shaft 15 in the said hangers 12 and 13, 90 but ordinarily it would not be necessary and would only add expense to the structure.

The upper face of the lower carrier-member 11 is made plane and it has a sunken groove 19 near its peripheral edge that forms 95 a circular race-way for the series of balls 20 that impinge or contact with the said plane lower face of the upper load-bearing member 6. Said upper face of the circular lower member 11 is duly spaced away from the 100 adjacent bottom face of the upper member 6, as best shown in Fig. 1, and the circular flange-portion 10 projects slightly below the level of said upper face of the member 11, whereby a suitable slightly spaced guard is 105 provided in which the member 11 can freely rotate within, and with the said balls 20 bearing against the underside of said upper member 6 for the various swivel movements required of the caster. 110

2
A central orifice 21 is provided in the lower member 11, such orifice having an inwardly-disposed horizontal flange 22 that contracts the upper part of the said orifice 21 and serves to freely accommodate the downwardly-projecting threaded shank or stud 9 on the bottom of member 6.

23 indicates a circular lock-ring whose central orifice or hole 23^a is screw-threaded 10 and whose upper peripheral edge is provided with a quarter-circle groove 24 that forms a race-way for the series of balls 25 that are of lesser diameter than that of the balls 20 to compensate for the difference in 15 diameter of the lock-ring 23 and that of the member 11 containing the race-way 19. The said balls 25 have a circular bearing in the angle formed by the flange 22 in the orifice 21 of member 11 and a suitable space is 20 allowed between the periphery of the lock-ring 23 and the inner wall of the said orifice 21, the upper face of said lock-ring lying in a plane below that of the lower face of said flange 22 and the lower threaded end 25 of the said shank or stud 9 extending only part way down into the threaded hole of the lock-ring and a threaded plug 26 being used in the remainder of the threaded hole of said lock-ring to set and lock the ring 23 in 30 place when the parts are assembled for use, with the balls 20 and 25 in their proper positions in their respective race-ways 19 and 24 for bearing purposes. A cross-slot 27 is provided in the screw-plug 26 to accommodate 35 the desired tool used in moving it to and from place in the threaded orifice of the lock-ring 23.

In the modified form of the two-part ball-bearing lock-ring device, seen in Figs. 4 and 40 5, I show the downwardly-disposed shank 9 in elevation but with its integral connection with the attaching-plate being shown broken off and the lower end of the said shank provided with a coarse screw-thread. 45 The lock-ring 23 is made with an upper peripheral ball-race 24, the same as in the form seen in Fig. 1, but it has a lower inverted-dome extension 28 that has a square-faced edge 29 for the use of a socket-wrench 50 or the like in turning it to and from place on the said threaded lower end of the shank 9. Said extension 28 is provided with a central orifice 30 that is screw-threaded, such thread being of a finer structure or pitch 55 than the coarser thread of the shank 9 above referred to and made to accommodate a screw or threaded pin 31 that takes the place of the screw-plug 26 seen in Fig. 1 and is preferably provided with a square head 32 for 60 turning it to and from place in the said dome-extension 28 with its top or inner end engaged in presser-contact with the lower end of the said shank 9 after the lock-ring has been turned up into the desired level for 65 the proper relation of the two sets of ball-

bearings, one between the said lock-ring and the other between the circular turn-table part of the lower member 11 of the caster and the girdled plane bottom-face of the upper attaching-plate member 6 of the 70 caster, as seen in Fig. 1. The difference in pitch of the screw-threads on the shank 9 and on the set-screw 31, shown in Fig. 4, serves to produce a decided lock for holding the upper and lower members of the caster 75 in their proper working relation, and including the proper relation and adjustment of the ball-bearing parts thereof. It is obvious that the set-screw 31 can be readily released or turned outwardly when it is desired to raise or lower the lock-ring of Fig. 4 on the shank 9 to make due allowance for 80 wear of the balls or of their race-ways or of the plane surfaces against which they contact in use.

Instead of the square extended-head 32 at the lower end of the set-screw 31 a cross-slot for a screw-driver could be easily substituted.

The caster is very easily assembled and 90 taken apart.

I claim:—

1. A wheel-caster for trucks and the like comprising an upper attaching-member having a plane lower face with a downwardly rimmed or flanged edge, a downwardly-disposed shank or stud projecting from the center of said lower face of the attaching-member and having a threaded lower end, a lower plane-faced carrier-member having an inwardly-flanged central orifice adapted to freely and concentrically accommodate the said shank, a circular ball-race in the upper plane-face of the carrier-member near its outer edge and provided with balls 95 adapted to bear free to roll or turn against the said plane lower face of the attaching-member, a pair of hangers or bracket-bearings extending from the bottom of the said lower carrier-member duly spaced apart and adapted to receive between them the supporting-roller of the caster that is mounted on a transverse shaft or pin that in turn rests in alined holes in the lower ends of the said hangers, a lock-ring having a central threaded opening adapted to engage with the lower threaded end of said shank 100 for interlocking the said upper and lower members of the caster in due relation free to permit the lower member to swivel on the upper member, a circular race-way constructed along the upper periphery of the lock-ring and provided with balls adapted to bear free to roll or turn in the central orifice of the lower carrier-member beneath 105 the inwardly-disposed flange at the upper end thereof, and a removable screw-plug inserted in the lower portion of the threaded opening of the lock-ring for setting and locking the said shank and ring in adjusted 110 115 120 125 130 135 140 145 150

- as well as locked position, substantially as shown and described.
2. In a wheel caster for trucks and the like, the combination of an upper or attaching member having a plane lower face with a downwardly-flanged edge, a central shank or stud projecting downwardly from the said lower face of the attaching-member and having its lower end screw-threaded, a lower centrally-orificed inwardly-flanged carrier-member having a plane upper face that is provided with a circular race-way near its peripheral edge, a series of balls in said race-way adapted to bear against the said lower plane-face of the upper attaching-member, a lock-ring having a threaded central orifice adapted to engage the said shank or stud and, also, having a race-way along its upper peripheral edge that is provided 10 with a series of balls adapted to contact with the inwardly-flanged upper edge of the central opening or orifice of the lower carrier-member, a screw-plug in the said threaded central orifice of the lock-ring, a 15 pair of spaced hangers or bracket-bearings extending downwardly from the lower face of said carrier-member and having holes in transverse alinement in the lower ends thereof, a horizontal shaft or pin mounted in said 20 alined holes in the hangers with its outer ends flush with the outer faces of the hangers, a vertical set-screw provided in a threaded hole made in the lower end of one or both of said hangers and with its inner 25 end adapted to engage a notch or socket made in the said shaft or pin in alinement with said vertical hole in the hanger or prevent dislodgment of said shaft or pin, and 30 a roller or wheel mounted on said shaft or pin between said hangers for rotating thereon in the movements of the caster over the floor-surface, substantially as shown and described.
3. In a wheel caster for trucks and the like, the combination of an upper attaching-member having a central shank or stud projecting downwardly and provided with a screw-thread of a relatively coarse pitch, a lower carrier-member having an inwardly-flanged central orifice adapted to freely and 35 concentrically accommodate said shank or stud, a circular race-way carrying a series of balls near the outer edge of the upper face or plane-table of said lower carrier-member, a pair of spaced hanger-arms projecting downwardly from the said carrier-member and having a transverse shaft or pin mounted in alined holes made in the lower ends of said hanger-arms, a caster-wheel mounted on the said shaft or pin between said hanger-arms a lock-ring having a central screw-threaded orifice or hole and a peripheral race-way along its upper edge, a downward or inverted-dome extension having a square-faced edge on the lower 40 face of said lock-ring and provided with a central orifice or hole that has a screw-thread of relatively lesser pitch than that of the coarser pitch of the screw-thread in the concentric shank-orifice made in the 45 lock-ring directly above said hole in the dome-extension and a vertical set-screw in said last-named dome-extension adapted to securely hold the said upper and lower members of the caster and their ball-bearings in adjusted position, substantially as 50 shown and described.

ROBERT A. ENDEBROCK.
